UNITED STATES PATENT OFFICE

HIRAM B. CANNON, OF MIDWAY, KENTUCKY, ASSIGNOR TO THE CARBORUNDUM COMPANY, OF NIAGARA FALLS, NEW YORK, A CORPORATION OF PENNSYLVANIA

COMBUSTION CHAMBER

Application filed August 15, 1925. Serial No. 50,399.

This invention relates to combustion chambers, and more particularly to combustion chambers employing fluid or pulperized fuel and which are made from tiles or sections of refractory material having heat-radiating qualities. While other materials are capable of realizing some of the heat-radiating qualities desirable in combustion chambers of the type to which this invention relates, the most satisfactory results are obtained by employing silicon carbide for such material.

In constructing combustion chambers of the materials referred to hereinbefore, difficulty has been encountered in producing chambers which are stable; that is to say, which do not require special braces and supports to keep them from collapsing or tumbling over. Still further difficulties have been encountered in providing combustion chambers capable of withstanding slight gas explosions therein, slight changes in gas pressure, and the throbbing of the burning gases, without collapsing the combustion chambers or knocking down the tiles or sections from which they are built. Still further difficulties have been encountered in providing gas-tight joints between the tiles of which these combustion chambers are constructed.

It is the general purpose and object of this invention to provide combustion chambers of the material referred to which will be free from the objections noted hereinbefore. I accomplish these objects in and through the construction and arrangement of parts shown in the drawings hereof, wherein Fig. 1 represents a central longitudinal sectional view through a combustion chamber constructed in accordance with my invention, the particular chamber being of the bottom-exhaust type; Fig. 2 a sectional view corresponding to the line 2—2 of Fig. 1; Fig. 3 a view corresponding substantially to the line 3—3 of Fig. 1, looking in the direction of the arrows; Figs. 4 and 5 are views corresponding respectively to Figs. 1 and 2 and showing a modification of my invention; and Fig. 6 a view corresponding substantially to the line 6—6 of Fig. 4.

Describing the parts by reference charac-

ters and first with particular reference to Figs. 1—3 inclusive, the combustion chamber comprises generally a top wall A, a bottom wall B, side walls C, rear wall D, a front wall E, and a partition wall F interposed between the top and bottom walls and extending from the front wall toward but spaced from the rear wall. The combustion chamber is provided with an opening G in the front thereof, between the partition F and the top wall A, for the supply of the combustible mixture thereto, and with an exhaust opening H in the bottom wall immediately adjacent to the front wall E. There is thus provided a combustion chamber having an upper pass and a lower pass communicating around the rear end of the partition F. This general type of combustion chamber is shown in my Patent No. 1,371,774 issued March 15, 1921, and in my application No. 713,186 filed May 14, 1924.

The walls A—F inclusive are made from a refractory material (preferably silicon carbide) in the shape of tiles which are assembled to form the walls. For the purpose of giving strength to the assembly and to overcome the objections noted hereinbefore, the tiles 1 of which the side walls C are composed are provided on opposed edges with tongues 2 and grooves 3. This enables them to be assembled conveniently end-to-end, as will appear clearly from Fig. 3, and to provide a strong connection between adjacent tiles. This construction also reduces gas leakage to a minimum, which reduction is still further increased by the use of silicon-carbide cement at the joints.

The individual tiles 4 which are employed for the top wall A are provided each with a tongue 5 at one end and a groove 6 at the other end, enabling them to be interlocked in the same manner as the tiles 1. The lower face of each tile 4 is also provided with a groove 6 adjacent each side edge adapted to receive the tongues 2 on the tops of the side tiles 1. The upper faces of the tiles 4 are also shown as provided with tongues 7 which are adapted to cooperate with tiles 1 thereabove, in the event that the combustion chamber is provided with another pass. How-

ever, if desired, the tongue 7 may be omitted from tiles which are known will constitute the top of a combustion chamber, the provision of tongues on all of the tiles tending to 5 standardize the construction and reduce the number of styles of tiles.

The individual tiles 8 of which the partition F is composed are identical with the tiles 4, the top tongues being indicated at 9, the 10 bottom grooves at 10, the end tongues at 11, and the end grooves at 12. The top tongues 9 are adapted to enter the bottom grooves 3 in the side tiles 1 thereabove while the bottom grooves 10 are adapted to receive the 15 tongues 2 on the tops of the side tiles 1 therebelow.

The individual bottom tiles 13 of which the bottom wall B is composed are provided each with an end tongue 14 and an end groove 20 15. In addition each tile 13 is provided in its upper face with a tongue 16 adjacent each side edge thereof and adapted to enter a groove 3 in the side of the tile 1 thereabove.

Each bottom tile 17 of the rear wall D is 25 provided at the top with a tongue 18 and at the bottom with a groove 19; also with a forwardly projecting tongue 20 near the bottom thereof adapted to enter the groove 15 of the adjacent bottom tile. In addition, each tile 30 has side tongues 21 adapted to enter the grooves 3 in the side tiles adjacent thereto.

The upper tile 22 of the back wall is provided with a groove 23 at its bottom adapted to receive the tongue 18 on the tile therebelow 35 neath with a forwardly extending tongue 24 at the top thereof and adapted to enter the groove 6 on the top tile adjacent thereto, and with a forwardly projecting tongue 25 at each side thereof adapted to enter the grooves 3 in the side tiles. Where it is contemplated using another pass above the upper pass shown herein, the tile 22 may have a short tongue 26 at each side thereof adapted to align with the tongues 7. The front tile E is 40 adapted to close the end of the lower pass and, for that purpose, requires only a groove at each side thereof adapted to receive the tongues 2 of the adjacent side tiles. The tile is shown, however, as provided additionally 45 with a forwardly projecting tongue 27 corresponding to the tongue 24 on the tile 22 and with a vertical tongue 28 at each side thereof, corresponding to the tongues 25. These tongues in the tile E as well as the groove 19 50 and tongues 21 in the tile 17 and the tongues 25 and 26 on the tile 22 enable the said tiles to be used in other and specifically different assemblies from the one shown herein.

The combustion chamber described herein, 60 although made of material having no great inherent strength, is stable, will withstand all ordinary incidents of use, and will prevent the leakage of gas therethrough, it being understood that gaseous fuel will be introduced 65 through the opening G and will be practically

entirely consumed in its passage through the two passes of the combustion chamber to the outlet H.

In Figs. 4-6 inclusive, there is shown a modification of my invention as utilized in connection with a combustion chamber having a top exhaust. In these views, A' denotes the upper wall, B' the lower wall, C' the side walls, D' the rear wall, E' the front wall, and F' the partition wall. The individual tiles of the top wall A' are preferably formed in the same manner as the corresponding tiles in Figs. 1 to 3 and the parts thereof are designated by the same reference characters, it being noted merely that the tongues 5 are shown as provided on the rear ends of the tiles and the grooves on the front ends, instead of vice versa, as shown in Figs. 1 and 3, and it being noted further that the tongues 7 are omitted, the tiles being designed with special reference to a two-pass furnace. The individual tiles of the top A' and of the bottom B' are also substantially identical with those used for the top and the bottom of the combustion chamber in Figs. 1-3, and the parts are designated by the same reference characters as are employed on the corresponding parts on Figs. 1-3, it being noted that the rearmost bottom tile is provided at its end with a tongue 14, adapting the combustion chamber for longitudinal extension, if desirable.

The individual tiles of the side C' are similar to the corresponding tiles shown in Figs. 2 and 3. Two styles of tiles 1^a and 1^b are employed for the sides, each having a tongue at one end thereof and a groove at the other end thereof, as is the case with the tiles 1. In addition, the tiles 1^a each have a tongue 2 at one of the horizontal edges thereof, and a groove 3 at the other horizontal edge. Each of the tiles 1^b has grooves 3^a in the upper and lower edges thereof. In addition, each of the tiles 1^a and 1^b has a ledge 29 arranged to project into the combustion chamber, with an angular notch 30 extending from said ledge to the adjacent horizontal edge of such tile. When assembled, the tiles 1^a and 1^b provide opposed channel-shaped seats 31 between the upper and lower ledges 20 for the tiles which comprise the partition F'. Each individual tile 32 of said partition is provided with straight side edges 32 and with reversely-arranged angular notches 33 on opposite ends thereof, this arrangement enabling the tiles to be assembled with a part of one tile projecting into a recess of the adjacent tile and forming a close joint with a part of such tile.

The rear end D' may be a single tile which is fitted into the space defined by the sides, top and bottom of the combustion chamber, being cemented in place.

In both forms of combustion chamber, the top, bottom and side walls and the partition wall are formed from individual tiles each

having a recess at one edge for the reception of the projecting part of the edge of an adjacent tile and each also having a projection at another edge adapted to enter a recess in the edge of an adjacent tile. It should be noted also that, in both forms of the invention, the tiles for the top and the bottom of the combustion chamber are generally interchangeable, as are also the tiles for the sides 5 of the combustion chambers. Furthermore, both forms of the invention result in the production of a combustion chamber which has the requisite stability and strength and which is sufficiently gas-tight to withstand 10 all ordinary incidents of use in commercial insulation.

Having thus described my invention, what I claim is:—

1. A combustion chamber having top, bottom and side walls and an end wall made from tiles of refractory material having high heat-radiating qualities, the sides comprising each an upper and a lower course of tiles interlocked at their front and rear edges, a 20 partition formed of tiles and interposed between the top course of tiles and the bottom course of tiles of each side wall, the tiles comprising the partitions being interlocked with each other and also being interlocked with 25 the tops of the tiles therebelow and with the bottoms of the tiles therebeneath, the tiles at the top and bottom of the chamber being also interlocked with the tiles constituting the sides, and the tiles constituting the rear wall 30 of the chamber being interlocked with each other and with the tiles in the top, bottom and sides.

2. A combustion chamber having top, bottom and side walls and an end wall made from tiles of refractory material having high heat-radiating qualities, the sides comprising each an upper and a lower course of tiles interlocked at their front and rear edges, a 40 partition formed of tiles and interposed between the top course of tiles and the bottom course of tiles of each side wall, the tiles comprising the partition being interlocked with each other and also being interlocked with the tops of the tiles therebelow and with the 45 bottoms of the tiles thereabove, the tiles at the top and bottom of the chamber being also interlocked with the tiles constituting the sides and the rear wall of the chamber being connected with the adjacent tiles 50 in the top, bottom and sides.

3. A combustion chamber having top, bottom, side and end walls and a partition extending from the front toward and spaced from the rear wall and interposed between 60 the top and bottom walls, the said walls and the said partition being composed each of tiles of refractory material having high heat-radiating quality, the tiles in each of said walls and in said partition being interlocked 65 to provide strength and prevent gas leakage,

the tiles of the top and bottom walls being also interlocked with the tiles of the side walls and the tiles constituting the rear wall being interlocked with the top, bottom and side walls, and the tiles of the partition being interlocked with the tiles of the side walls: 70

4. A combustion chamber having top, bottom and side walls and a rear wall and a partition extending from the front toward and spaced from the rear wall and interposed between the top and bottom walls, the said walls and the said partition being composed each of tiles of refractory material having high heat-radiating quality, the tiles in the top, bottom and side walls and in said partition being interlocked to provide strength and prevent gas leakage, the tiles of the top and bottom walls being also interlocked with the tiles of the side walls and the tiles of the partition being interlocked with the tiles in the side walls. 75

5. A combustion chamber having top, bottom, side and front and rear walls and a partition extending from the front toward and spaced from the rear wall and interposed between the top and bottom walls, the said walls and the said partition being composed each of tiles of refractory material having high heat-radiating quality, the tiles in each of said walls and in said partition being interlocked to provide strength and prevent gas leakage, the tiles of the top and bottom walls being also interlocked with the tiles of the side walls and the tiles constituting the rear wall being interlocked with the top, bottom and side walls, the tiles constituting the said partition extending entirely across the chamber and supporting and interlocked at their side edges with the tiles thereabove in the side walls and being supported by and interlocked with the tiles therebelow in said side walls. 90

6. A combustion chamber having top, bottom, rear and side walls and a partition extending from the front toward and spaced from the rear wall and interposed between the top and bottom walls, the said walls and the said partition being composed each of tiles of refractory material having high heat-radiating quality, the tiles in each of said walls and in said partition being interlocked to provide strength and prevent gas leakage, the tiles of the top and bottom walls being also interlocked with the tiles of the side walls, and the tiles constituting the said partition extending across the chamber and being interlocked at their side edges with the tiles thereabove and therebelow in the side walls, and the rear wall being fitted to the side, top and bottom walls. 110

7. A combustion chamber of the character set forth having top, bottom and side walls and a partition extending from the front toward the rear wall and interposed between the top and bottom walls, the said 125

top, bottom and side walls as well as said partition being formed of individual tiles of refractory material having high heat-radiating quality, each tile having a recess at one edge for the reception of a projecting part on the edge of an adjacent tile and also having a projection at another edge adapted to enter a recess in an adjacent tile whereby the said top, bottom and side walls of the chamber are interlocked to strengthen the construction as a whole and to prevent gas leakage, the tiles constituting said partition extending across said chamber and interlocking at their edges with the tiles thereabove and therebelow, and the rear wall of said combustion chamber being fitted to said side, top and bottom walls.

8. A refractory muffle structure for use in high temperature furnace operations comprising a plurality of flat dense refractory plates having a length equal to the width of the structure and provided with tongues and grooves interfitting to form continuous top and bottom walls of the muffle, and a plurality of plates of similar material extending between the top and bottom which are provided with tongues and grooves interfitting to form the muffle sides, said side plates being arranged upon the bottom plates and adapted to support the top plates, said plates having interfitting tongue and groove connections, thereby providing an integral self-supporting structure adapted to effectively resist the heat changes encountered in high temperature operations.

9. A refractory muffle structure for use in high temperature furnace operations comprising a plurality of interchangeable flat dense refractory plates forming the top and bottom of the muffle, and interchangeable side plates supported on the bottom plates and in turn supporting the top plates, each of the top and bottom plates extending the full width of the muffle and the side plates extending between the top and bottom of the muffle, said plates having interfitting tongue and groove connections to form self-supporting muffle walls.

10. A refractory chamber for use in high temperature furnace operations especially adapted for transmitting heat by radiation through the walls thereof, the said chamber comprising a plurality of flat dense refractory plates having a length equal to the width of the structure and provided with tongues and grooves interfitting to form continuous top and bottom walls of the chamber, and a plurality of plates of similar material extending between the top and bottom which are provided with tongues and grooves interfitting to form the chamber sides, said side plates being arranged upon the bottom plates and adapted to support the top plates, said plates having interfitting tongue and groove connections, thereby providing an integral

self-supporting structure adapted to effectively resist the heat changes encountered in high temperature operations.

11. A refractory chamber for use in high temperature furnace operations especially adapted for transmitting heat by radiation through the walls thereof, the said chamber comprising a plurality of interchangeable flat dense refractory plates forming the top and bottom of the chamber, and interchangeable side plates supported on the bottom plates and in turn supporting the top plates, each of the top and bottom plates extending the full width of the chamber and the side plates extending between the top and bottom of the chamber, said plates having interfitting tongue and groove connections to form self-supporting chamber walls.

In testimony whereof, I hereunto affix my signature.
